PUMP ENTRY VANE CONSTRUCTION

Russell R. Curtis, Dayton, Ohio, assignor, by
mesne assignments, to Thompson Products,
Inc., a corporation of Ohio

Application November 29, 1943, Serial No. 512,263

4 Claims. (Cl. 222—383)

1

This invention relates to a device for breaking up a vortex of whirling liquid at the inlet of a centrifugal type pump.

Specifically the invention relates to an entry vane and filter screen assembly for centrifugal type booster pumps adapted for use in an airplane fuel system.

The invention will hereinafter be specifically described in connection with airplane fuel systems, but it should be understood that the invention is not limited to such use, being broadly applicable to any system embodying the use of centrifugal type pumps or other devices which tend to whirl liquid.

In airplane fuel systems having centrifugal type booster pumps equipped with agitators or beaters for liberating bubbles of gas and vapor from fuel entering the pump, there is a tendency for the fuel flowing to the pump to form a whirling vortex especially if the fuel is directed to the pump through a conduit that is not much larger in diameter than the diameter of the pump inlet. In such systems the liberated bubbles of gas and vapor should rise around the liquid flowing to the pump and eventually reach the surface of the pond of fuel where they can burst to discharge the gases and vapors. A whirling vortex of fuel flowing downwardly to the pump, however, may trap the rising stream of bubbles, thereby building up a layer of bubbles or a slug of vapor which might eventually find its way into the pump. Since such a slug of vapor offers very little resistance to the pump, the impeller speed of the pump increases over its normal speed and results in increased agitation tending to disperse the gases or vapors back through the inlet of the pump. Such dispersement, of course, permits the liquid fuel to again flow into the pump whereupon the impeller speed will be reduced. Thus slugs of liquid and pockets of gas or vapor are alternately acted upon by the impeller and pulsations occur in the pump speed with resulting pulsations of the liquid fuel pressured by the pump. Such alternate pumping of gases and vapors is, of course, highly undesirable in fuel systems where a supply of fully liquid fuel under constant pressure must be maintained for efficient operation.

According to this invention, a baffle is mounted in the inlet of the pump and extends for a considerable distance into the liquid about to enter the pump. This baffle has broad opposed side faces effective for breaking up the whirling of the fuel so that the liquid will be directed axially into the pump. Since it is also desirable to screen

2

or filter the liquid being fed to the pump, this baffle is conveniently carried by a cup-shaped screen mounted over the pump inlet. The baffle projects from the mouth of the cup-shaped screen into the throat opening or inlet opening of the pump where it terminates in closely spaced relation to the pump impeller. Thus the projecting portion of the baffle will prevent the formation of a secondary whirlpool within the pump inlet.

It is, then, an object of this invention to provide an entry vane construction for centrifugal type pumps which is carried by a screen or filter adapted to be mounted on the pump.

A still further object of the invention is to provide a combined filter and baffle construction for centrifugal type pumps.

Another object of the invention is to provide an attachment for centrifugal type pumps which will effectively prevent whirling of fuel about to enter the pump.

Still another object of the invention is to provide an entry vane construction for booster pumps which is readily mounted on said pumps without change in pump construction.

Other and further objects of the invention will be apparent to those skilled in the art from the following detailed description of the annexed sheet of drawings which, by way of preferred example, illustrates one embodiment of the invention.

On the drawings:

Figure 1 is a broken and fragmental vertical cross-sectional view, with parts in elevation, of a booster pump, a fuel tank, and a flow connection therebetween, illustrating the entry vane and filter construction of this invention mounted on the booster pump.

Figure 2 is a fragmental vertical cross-sectional view, with parts in elevation, taken along the line II—II of Figure 1.

Figure 3 is a bottom plan view of the filter and entry vane construction according to this invention.

As shown on the drawings:

45 In Figure 1 the reference numeral 10 designates a tank having a vent 11 and holding a pond P of gasoline or other volatile engine fuel. A booster pump assembly 12 is connected in flow communication with the tank 10 by means of a pipe member 13. This pipe member 13 is formed as an elbow with one end being connected to a side wall 14 of the tank adjacent the bottom wall 15 of the tank. The elbow type flow connection between the tank 10 and booster pump assembly

50 12 is used in installations which do not have suf-

sufficient pump mounting space immediately adjacent the tank. It is preferable to mount the pump 12 directly on the bottom wall 15 of the tank but in some installations the bottom wall of the tank is not spaced sufficiently from an airplane wing skin, or the like to provide room for the pump.

The elbow pipe 13 has a radially outturned flange 16 at the lower end thereof. The pump 12 includes a casing 17 defining a pump volute chamber 18, a discharge outlet 19 communicating with the volute chamber 18, and a shaft well 20 receiving therethrough a drive shaft 21. An electric motor or other prime mover (not shown) drives the shaft 21. The casing 17 has an outturned flange 22 therearound receiving bolts 23 therethrough having heads seated on the flange 16 of the elbow pipe 13 and nuts 23a thereon underlying the flange 22 to mount the pump assembly 12 on the pipe 13. A gasket 24 is preferably interposed between the flange 16 of the pipe 13 and the flange 22 of the pump casing.

The casing 17 has an annular open end communicating with the volute chamber 18 through a cylindrical bore 25 and terminating in a flat end face 26.

A throat ring 27 is mounted in the bore 25 and has a radial flange 28 snugly fitting into the pipe 13 and seated on the end face 26 of the casing 17.

The throat ring 27 has an outwardly flaring conical mouth 29 converging to a circular opening 30 of smaller diameter than the bore 25 so that the bottom of the ring forms a top wall for the volute chamber 18. The opening 30 forms the inlet to the pump.

An impeller 31 is mounted on the shaft 21. This impeller is preferably in the form of a hubbed disk with a hub 31a secured on the shaft 21 and a flat disk portion 31b spanning the opening 30 and overlying the shaft well 20. Upstanding vanes 32 are formed on the disk portion 31b. These vanes 32 have outer end portions 32a underlying the throat ring 27 to cooperate therewith for forming pumping channels between the opening 30 and the volute chamber 18. The vanes will centrifugally pump fuel to the volute chamber 18 and through the volute chamber to the discharge line 19.

The vanes 32 also have inner end portions 32b under the opening 30 of the throat ring 27 where they are fully exposed and are uncovered. The inner ends 32b of the vanes 32 serve as agitators or beaters for liberating bubbles B of gas and vapor from the fuel before the fuel enters the pumping channels. These bubbles of gas and vapor flow outwardly along the diverging mouth 29 of the throat ring 27. The pump is arranged so that only fully liquid fuel is pressured and so that vapors and gases are rejected from the pump to flow away from the pump in bubble form.

In accordance with this invention a cup-shaped metal screen 35 is provided to filter fluid flowing into the pump. This screen 35 has a cylindrical side wall 36 of large enough diameter to surround the divergent end of the mouth 29 of the throat ring 27. The side wall 36 projects for a considerable distance in advance of the pump into the pipe 13 and a wire screen 37 bridges the end of the cylinder at a point remote from the pump.

The open end of the cylinder receives therearound a metal ring 38 having an upstanding flange 38a soldered or otherwise secured to the screen. This ring 38 is apertured at intervals therearound to receive the cap screws 39 therethrough. Thus cap screws 39 extend through the

flange 28 of the throat ring 27 and are threaded into the casing 17 to hold the screen assembly and the throat ring on the casing 17.

The screen assembly 35 is readily made by soldering the mounting ring 38 around one end of a screen cylinder and by pressing a screen disk 37 into the other end of the cylinder to leave a flange 37a on the disk abutting the inner face of the cylinder. This flange is then conveniently soldered or otherwise secured to the cylinder.

A baffle or vane 40 preferably composed of a metal sheet or plate is disposed in the cylinder 36 to lie axially along the length of the cylinder for dividing the chamber provided by the cylinder into two adjacent compartments each of which communicates at its lower end with the opening 30 of the throat ring. This vane 40 is conveniently soldered to the cylindrical wall 36 and extends from closely spaced relation from the end wall 37 out of the open end or mouth of the screen. The projecting portion of the plate has tapered edges 40a in spaced parallel relation with the outwardly flaring wall 29 of the throat ring so that the end of the plate can lie immediately adjacent the opening 30 of the throat ring.

A screen cup assembly carrying a dividing plate or baffle is thus provided for mounting on the inlet throat of a booster pump so that the plate will project into the inlet throat and terminate in closely spaced relation to the impeller of the pump.

Fuel can flow freely from the tank 10 through the pipe 13 and through the pump 12 to the discharge outlet 19 thereof even when the pump is at rest since the inlet 30 and the outlet 19 of the pump are in constant communication. When the pump is operated the outer portions 32a of the vanes 32 on the impeller 31 will centrifugally discharge fuel through the volute 18 into the discharge line 19 while the inner pumping vane portions 32b exposed to the inlet opening 30 will beat out bubbles B of gas and vapor from the liquid fuel.

Rotation of the impeller 31, however, may create a vortex or whirling mass of fuel in the pipe 13, the particles of which rotate in the same direction as the impeller and move in a corkscrew fashion toward it. The bubbles B are thrown out by the vanes along the outwardly flared surface 29 of the throat 27 and, being lighter than the liquid fuel, rise within the vertical leg of the elbow member 13 adjacent the walls of this leg. The light bubbles of gas and vapor rising in the vertical leg of the elbow member tend to flow into the path of liquid flowing through the horizontal leg of the elbow member and tend to be drawn toward the impeller with the liquid fuel. A layer or mass of bubbles may thus form across the inlet throat of the pump, cutting off flow of liquid into the throat and permitting the impeller vanes to operate in a gas. This, of course, will speed up the pump by reason of the low inertia of the gas and vapor bubbles as compared with the inertia of the liquid fuel. Speeding up of the impeller creates additional agitation which forces the bubbles outwardly along the tapered surface of the throat ring, thereby breaking up the pocket of the vapor and gas. As soon as this pocket is broken up a slug of liquid fuel will then flow into the inlet throat and the speed of the impeller will be reduced by the inertia of the liquid. As a result, alternate formation of vapor pockets and beating of slugs of liquid, together with alternate variations in impeller speed, causes pulsation

tions in the delivery of fuel to the outlet 19 of the pump.

This pulsating delivery is prevented by the baffle 48 which extends into the pipe 13 in advance of the inlet 30 of the pump and provides wide faces for breaking up the whirling mass of fuel adjacent the pump inlet and for directing the fuel axially into the pump inlet. The baffle 48 does not restrict the separation of gas and vapor bubbles from the liquid fuel caused by the agitating impeller vanes and the bubbles are thrown outwardly along the outwardly flaring walls 29 of the throat ring where they will rise upwardly as shown in Figure 1 around the descending column of liquid fuel. A counter-current circulation of fuel and bubbles is thus created in the elbow member 13 with the bubbles rising through the fuel adjacent the walls of the elbow member and with the fully liquid fuel being fed axially toward the impeller to the inlet throat. The screen 35, of course, filters out any solid matter such as dirt, rust, and the like and prevents the same from reaching the pump.

The screen and vane construction is readily mounted on any type of pump and the pump construction need not be modified.

It will, of course, be understood that various details of construction may be varied through a wide range without departing from the principles of this invention and it is, therefore, not the purpose to limit the patent granted hereon otherwise than necessitated by the scope of the appended claims.

I claim as my invention:

1. A filter and vane construction for a centrifugal type pump having a tapered inlet throat which comprises a cup-shaped metal screen, a mounting ring secured around the mouth of the screen for attaching the screen to the throat of a pump, and a vane in said cup-shaped screen dividing the screen axially and having a portion projecting beyond the mouth of the cup, said portion having tapered edge walls for lying closely adjacent the tapered inlet throat of the pump to provide an escape path along said tapered inlet throat of gas bubbles formed in the pump inlet.

2. In a pump construction including an inlet throat with an outwardly flaring mouth, an impeller having pumping vanes underlapping said throat to centrifugally whirl and pump fluid received from the throat together with uncovered agitating vanes exposed to the throat opening for acting on fluid flowing to the pumping vanes and effective for ejecting bubbles of gas and vapor from the fluids before the fluids reach the pumping vanes, the improvements of an inverted cup-shaped screen overlying the throat and having a mounting ring around the mouth thereof seated on top of the throat outwardly from the throat mouth, means attaching the mounting ring to the throat, and a baffle bisecting the cup-shaped screen secured to the side wall of

the screen and having a tapered end depending from the mouth of the screen into the outwardly flaring mouth of the throat in close proximity to said throat mouth and to said agitating vanes, said baffle having side faces effective for breaking up the whirling of fluid flowing to the pumping vanes while directing the fluid substantially axially of the throat opening and permitting the escape of said bubbles of gas and vapor along said outwardly flaring mouth of the throat and through the screen.

3. In an assembly having a tank with an apertured wall and a booster pump mounted on said apertured wall having an outwardly flaring inlet throat in the aperture of the wall for receiving liquids from the tank, the improvements of an inverted screen cup overlying said throat and extending into the tank for an appreciable distance, and an upstanding baffle plate in said cup secured to the side wall thereof and having a tapered end portion depending from the cup into the throat in close proximity with the outwardly flaring mouth of the throat to provide opposed broad faces for breaking up whirling of fluid about to enter the pump while directing fluid in the cup axially into the pump.

4. In an assembly having a tank with a pipe extending from the lower portion thereof and having a free end with an outturned flange therearound, and a booster pump having an open topped pump casing with an outturned flange therearound clamped to the outturned flange of the pipe, the improvements of a conical mouthed throat ring seated in the open top of the pump 35 casing and having a radial flange snugly fitting into the pipe, an inverted screen cup having a mounting ring around the mouth thereof, means attaching the mounting ring to the throat ring to secure the cup to the throat ring, said cup projecting into the pipe for an appreciable distance to provide an inlet filter for the pump, and an upstanding baffle plate bisecting said cup and secured to the side wall thereof, said baffle plate having a tapered depending portion projecting 45 beyond the mouth of the cup into close proximity with the mouth of the throat ring.
